UNITED STATES PATENT OFFICE.

EDWARD C. BACHFIELD, OF INDIANAPOLIS, INDIANA.

RAILWAY CROSS-TIE.

1,256,096.

Specification of Letters Patent. Patented Feb. 12, 1918.

Application filed April 16, 1917. Serial No. 162,243.

To all whom it may concern:

Be it known that I, EDWARD C. BACHFIELD, a citizen of the United States, residing at Indianapolis, in the county of Marion and 5 State of Indiana, have invented certain new and useful Improvements in Railway Cross-Ties, of which the following is a specification, reference being had therein to the accompanying drawing.

10 This invention relates to improvements in railway cross ties.

The object of the invention is to provide a cross tie or cross tie blocks comprising a seat for the rails and a locking clamp to 15 secure the rails in the seats. In this connection it is a further object to make the ties or tie blocks of a solid character, as of cast iron or any alloy which will render them solid so that they will not yield, as in the case of 20 wood.

A further object of the invention is to provide for the ready expansion of the rails under heat and contraction under cold by 25 securing or fastening each rail to the tie or tie block only at a point intermediate its ends, approximately midway its length, the remainder of the ties or tie blocks being clamped only to the rails. In this way each 30 rail may expand and contract without affecting any other rail. This feature of my invention is thus distinguished from the common construction of interconnecting all 35 the rails by fish plates and bolts with the present objectionable fact that when all the rails expand they force the track outward at the curves and when they all contract force the track inward at the curves, these 40 distortions or movements acting to shift the cross ties longitudinally at the points thus affected by the expansion and contraction. All this I avoid by my new arrangement.

In the accompanying drawings, Figure 1 is a plan view of two of my improved ties with a portion of one rail at either side; Fig. 45 2 is an end elevation of one of my improved ties and of two rails held therein; Fig. 3 is a perspective view of one end of a tie; Fig. 4 is a perspective view of the locking clamp detached therefrom; Fig. 5 is a plan view of 50 that portion of my invention that relates to securing the rails at or near the middle to the ties; and Fig. 6 is a partial section and partial side elevation of one of the ties showing the manner of fastening the tie rod to 55 the end portions.

Referring to Fig. 1, the numeral 1 design-

nates the ends of the cross ties which are in the nature of blocks of cast metal or alloy adapted to constitute solid unyielding blocks or ties. Each two of the portions or blocks 60 1 are connected together by a tie rod 2, preferably in the form of a pipe about which the blocks are cast. To further insure the firm connection of the blocks to the tie rod or pipe the latter has burs or enlargements 3 65 about which the material of the blocks binds. But some other mode of securely connecting the blocks and tie rods may be employed.

The tie blocks are constructed with a rail seat 4 overhung at one side by a flange 5 and 70 at the other side by an inclined wall 6. The rail base is fitted into the seat 4 with one side of the base locked under the flange 5 and the other side of the base clamped or secured by a locking clamp 7. This clamp has a web 8 75 which fits between the rail base and the inclined wall 6. The wall 6 is slightly inclined longitudinally from the rail base so as to leave a tapering space between the rail base and the wall 6 for the reception of the 80 web 8 which for this reason acts like a wedge, so that the farther the clamp is advanced the tighter it will bind that side of the rail base. To forcibly advance the clamp a headed screw 9 extends through a 85 lug 10 and screws into an orifice 11 in the block. In this way by turning the screw 9 the clamp is forced against the undercut wall and the rail and the latter is securely locked under the flange 5. Then to secure 90 the clamp in its final position a lock bolt 12 is inserted through the opening 13 and screwed into the orifice 14.

Thus, the rail is firmly secured to the tie or tie block as respects all directions, save 95 only that the rail may readily expand and contract.

By this construction and by means of the solid character of the ties or tie blocks the rails are held and are also supported with 100 the minimum vibration.

With these ties or tie blocks mounted upon a solid base or bed practically all vibration of the rails is eliminated. In my application filed of even date herewith relating to improvements in railway-beds I have set forth such a bed as will afford a non-yielding or 105 vibrating base for cross ties of this character.

I will now refer to the other feature of 110 my invention, namely, that relating to the provision for allowing the rails to expand

and contract without shifting the radial position of the rails at curves in the road. The ties or tie blocks are provided with holes 15 to receive bolts or pins 16 which pass through holes in the rail base, all as indicated particularly in Figs. 2, 3 and 5. From the latter figure it will be observed that this attachment of the rails to the ties or tie blocks is at or near the middle of each rail, 10 while the adjacent ends of the succeeding rails are unfastened to the ties or tie blocks except through the clamp before referred to. This is shown also in Fig. 5. A slight clearance, according to the size of the rail 15 and the known climatic conditions, is left between the ends of each two rails for expansion and contraction.

Under this organization I am enabled to completely avoid the radial shifting of the 20 rail bed or ties at curves in the road by reason of expansion and contraction of the rails.

I would further observe that as to the function or office of the clamp 7, it operates 25 to sustain the rail, largely in and of itself acting in combination with the tie or block, irrespective of the action of the overhanging flange 5. In other words, in addition to the relation of the clamp 7 to the overhanging 30 flange 5, the clamp 7 operates also, in a sense independently, in aiding and sustaining the rail in its true position.

While I have shown and described one embodiment of my invention it will be understood that the same has been chosen for the purposes of illustration only, and that I do not desire to be limited to the details of construction shown and described, for 35 obvious modifications will occur to a person skilled in the art.

Copies of this patent may be obtained for five cents each, by addressing the "Commissioner of Patents, Washington, D. C."

Having thus fully described my invention, what I claim as new and desire to secure by Letters Patent, is:—

1. In a rail fastening device, a tie block having a rail seat bordered by an overhanging flange, and an inclined wall, a clamp having a depending web fitting between the rail seat and said inclined wall, a portion of said clamp being positioned over the tie block and a bolt passing through the portion of the clamp over said tie block and into the block. 45

2. In a rail fastening device, a tie block having a rail seat bordered by an overhanging flange and an inclined wall, said wall 55 being also longitudinally inclined, a longitudinally inclined clamp having a depending web fitting between the rail and the inclined wall, a bolt passing through said clamp and into said tie block, a lug depending from said clamp, and a bolt passing through said lug and into said tie block. 60

3. In a rail fastening device, a tie block having a rail seat bordered by an inclined 65 wall, a clamp having a longitudinally inclined edge abutting the inclined wall, and a bolt passing through a portion of said clamp and into said tie block.

4. In a rail fastening device, a tie block having a rail seat bordered by an inclined 70 wall, a clamp having a longitudinally inclined edge abutting said inclined wall, a bolt passing through the clamp and into the portion of the tie block having the inclined wall, and a second bolt passing through a 75 portion of the clamp and into the tie block and serving to force the clamp to clamping position.

In testimony whereof I affix my signature.
EDWARD C. BACHFIELD.
